VALVED BAG

Charles V. Brady and August F. Ottinger, St. Louis, Mo., assignors to Bemis Bro. Bag Company, St. Louis, Mo., a corporation of Missouri

Application September 24, 1948, Serial No. 50,898

9 Claims. (Cl. 150—9)

1

This invention relates to valved bags, and more particularly to an improved valved bag having an insert type of valve sleeve.

Among the several objects of the invention may be noted the provision of a valved bag embodying reinforcement means at the bag mouth facilitating handling and packing; the provision of a valved bag of the class described having a label strip extending peripherally around the upper margin of the bag; the provision of a bag of this class embodying an adhesively secured valve sleeve insert; the provision of a bag of this class embodying a valve insert which is more firmly held in place; and the provision of a valved bag such as described which is economical to manufacture. Other objects will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which several of various possible embodiments of the invention are illustrated,

Fig. 1 is a plan view of a composite web from which the bag of this invention is made;

Fig. 2 is a plan view of a folded and stitched bag blank made from the web of Fig. 1;

Fig. 3 is a plan view of the Fig. 2 blank after an initial step performed in the manufacture of the bag;

Fig. 4 is a top view of the blank of Fig. 3 after another step;

Fig. 5 is a top view of the Fig. 4 blank after a further step;

Fig. 6 is a top view similar to Fig. 5 after an additional step;

Fig. 7 is a plan view of the finished bag made from the blank of Fig. 6;

Fig. 8 is an enlarged perspective view of the valve of the Fig. 7 bag;

Fig. 9 is an enlarged section of a portion of the bag taken in a plane similar to that of Fig. 7 but passing widthwise through the center of the bag;

Fig. 10 is a view similar to that of Fig. 9 showing another valve embodiment;

Fig. 11 is a view similar to that of Fig. 5 showing a further valve embodiment;

Fig. 12 is a top view after an intermediate step in the formation of a valve in the Fig. 11 blank;

Fig. 13 is a view similar to that of Fig. 9 showing the finished valve of the Fig. 12 embodiment;

2

Fig. 14 is a view similar to that of Fig. 5 showing an additional valve embodiment;

Fig. 15 is a top view after an intermediate step in the formation of a valve in the Fig. 14 blank;

5 Fig. 16 is a view similar to that of Fig. 9 showing the finished valve of the Fig. 15 embodiment.

Figs. 9, 10, 13 and 16 show in dotted lines filling tubes inserted through the valves of the invention.

Similar reference characters indicate corresponding parts throughout the several views of the drawings.

Referring to Fig. 1, the bag of this invention is shown to be made from a blank 1 cut from a composite web comprising bag material 3 and a reinforcement strip or band 5. The bag material 3 may be of any nature such as textile or paper-lined textile. The relatively narrow strip 5 may be of paper or the like and is secured by adhesive 7 to the margin of web 3, preferably the full length thereof. The strip 5 may be secured to the bag web by a substantially continuous method of manufacture. The strip 5 may be pre-printed with suitably spaced advertising indicia for purposes to be described.

Referring to Fig. 2, the blank 1 is folded upon itself along a longitudinal central line of folding A, transverse to strip 5, so that the strip 5 is inside the bag. The adjacent marginal edges 9 opposite fold A and the adjacent marginal edges 11 opposite the strip 5 or at the bottom of the blank are sealed as by stitching 13 leaving the mouth 21 open. The blank is then reversed to provide inturned side and bottom seams as shown in Fig. 3. If desired, the bag length reversing step and the inturned seams may be eliminated by folding the blank 1 with the reinforcement strip 5 on the exterior thereof and seaming as before. To facilitate the formation of a tucked-in valve flap 15, the folded and seamed blank or bag length may be provided with fold lines B angling across both front and rear bag walls at the upper corners thereof adjacent fold A to define a triangular segment 15 bisected by the fold A. The triangular segment 15 of the bag body is tucked inwardly within the bag body to provide a tucked-in valve flap as shown in Fig. 4. The tucked-in valve flap is traversed at its inner edge 17 by a portion of the reinforcement strip 5.

A valve sleeve insert 19 comprising a generally rectangular blank of flexible sheet material, preferably paper, is secured to the inner edge 17 of the valve flap 15. The insert 19 is initially directed outwardly over the valve flap 15 and is

secured at its inner edge to the inner edge 17 of the valve flap by a relatively narrow strip of adhesive 21. The valve sleeve 19 is then folded inwardly along the line C adjacent the outer edge of its adhered portion 23 to provide an inwardly directed valve extension 25 (Fig. 6). The valve flap 15 and valve sleeve 19 are then folded upon themselves along line D and the edges of the bag mouth 27 brought together and closed as by stitching 29 (Fig. 7). The mouth seam stitching also anchors the upper edges of the valve extension. The above described order of steps is chosen to simplify the discussion, as the valve sleeve 19 may be secured to the bag length prior to the formation of the tucked-in valve flap 15. The finished bag has a reinforcement strip 5 which extends peripherally around the closed bag mouth and down within the tucked-in valve flap. The exterior portion of strip 5 may bear suitable advertising indicia (indicated by the letters X Y Z) and serve as a label area. The exterior portion of strip 5 also strengthens the bag mouth to facilitate applying a bag upon a filler tube 30 (Fig. 9), and supporting same on the tube. The portion of the reinforcement strip 5 which traverses the valve flap 15 has the advantage of permitting a paper to paper adhesive attachment of the valve insert 19 to the valve flap. If desired, the edges of the sheet 19 may be spaced from the bag mouth so as not to be anchored by the mouth stitching 29.

Another embodiment of this invention is illustrated in Fig. 10. The construction is identical with that of the previously described embodiment up to and including Fig. 5. The bag mouth 27 is then closed and seamed so that the unadhered portion 25 of valve sleeve 19 is left extending outward over the valve flap 15 to provide a valve extension. The mouth seam 29 is shown to carry over onto the outwardly directed valve extension 25 to anchor together its upper edges though this need not be done. After the bag is filled, the valve is closed by folding or rolling up and tucking in extension 25. The result is what is called a tuck-in valve.

A further embodiment is shown in Figs. 11-13. A tucked-in valve flap 15 is formed as before and a valve sleeve insert 31 is secured to the inner edge 17 of the valve flap so that it is initially directed inwardly over the bag mouth 27 (Fig. 11). The unadhered portion 33 of the valve extension is in this case folded outward along a line E adjacent the outer edge of the adhered portion 35 to provide a valve extension which may later be tucked in for closure. The valve sleeve 31 is folded upon itself and the bag mouth closed and seamed as before (Fig. 13).

Figs. 14-16 illustrate an additional valve embodiment of the outwardly directed type adapted to be tucked in for closure. In this form, a relatively longer valve sleeve insert 37 is secured by the adhesive area 23 adjacent the inner edge 17 of the valve flap 15. The valve sleeve 37 is then folded outwardly along a line F spaced inwardly from the inner edge 17 of the valve flap to provide an outwardly extending valve extension 39. The bag mouth may be closed and stitched as before (Fig. 16). However, it will be noted there is provided a substantial four ply portion 41a of the valve sleeve which is anchored by the mouth stitching 29 as contrasted with the relatively small upper corners of the valve sleeve which are anchored by stitching 29 in the previously described embodiments of Figs. 10 and 13. The valve is closed by folding or rolling up and tuck-

ing in the valve extension portion 39. This construction results in an even stronger valve less likely to be torn from the bag body.

It is preferable that the width W of the strip 5 be less than the inward extension or depth U of the valve flap, as indicated in Figs. 3, 7, 9, 10, 13 and 16 for example. This facilitates the ease with which the break is accomplished at K (see Figs. 3 and 6-10) when the valve flap is turned in. This is due to the fact that by this means the break is made to occur in a part of the bag wall which is not reinforced by the strip.

Thus it will be seen that the invention provides for a valve extension which has a stronger attachment to the tucked-in valve flap by reason of attachment of the extension to a paper band forming an inner face of said valve flap. This is particularly true in the case of a bag which would otherwise present a fabric face inside of the flap, to which the extension might not adhere as well as it does to paper. The paper band also extends from the valve flap out into the bag walls around the top of the bag thus strengthening the attachment of the paper band to the valve flap portions. In addition, this strengthening extension is positioned outside of the bag so that it may, if desired, be used for advertising indicia.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

We claim:

1. A valved bag having a tucked-in valve flap at one corner thereof, a discrete reinforcing strip 10 extending around the bag at the valve flap end thereof traversing the margin of the valve flap and secured to the bag proper, one edge of the strip being substantially coincident with said end of the bag, and a valve sleeve having one margin 35 secured to the portion of the strip traversing the margin of the valve flap.

2. A valved bag having a tucked-in valve flap at one corner thereof, a discrete paper reinforcing and label strip extending completely around the bag at the valve flap end thereof traversing the margin of the valve flap and adhered to the outside of the bag proper, one edge of the strip being substantially coincident with said end of the bag and the width of the strip being less than the depth of the valve flap, and a paper valve sleeve having one margin adhered to the portion of the strip traversing the margin of the valve flap.

3. A valved bag comprising a rectangular blank 60 of bag material having a discrete relatively narrow reinforcing strip extending along one margin thereof with one edge of the strip substantially coincident with the edge of the blank at said margin, the blank being folded along a line transverse to the strip with its marginal edges adjacent one another and seamed to form the bag, a corner of the bag on the fold line being tucked in to provide a valve flap with a portion of the strip traversing the margin of the flap, and a 65 valve sleeve having one margin secured to the portion of the strip traversing the margin of the flap.

4. A valved bag comprising a rectangular blank 70 of bag material having a discrete relatively narrow paper reinforcing and label strip extending

along one margin thereof, the strip being adhered to the blank with one of its edges substantially coincident with the edge of the blank at said margin, the blank being folded along a line transverse to the strip with its marginal edges adjacent one another and seamed to form the bag, the strip extending around the outside of the bag, a corner of the bag on the fold line being tucked in to provide a valve flap with a portion of the strip traversing the margin of the flap, the strip being narrower than the depth of the flap, and a valve sleeve having one margin adhered to the portion of the strip traversing the margin of the flap.

5. A valved bag as set forth in claim 4 wherein the sleeve extends into the bag from the margin of the valve flap.

6. A valved bag as set forth in claim 4 wherein the sleeve extends out of the bag from the valve flap.

7. A valved bag as set forth in claim 4 wherein the sleeve is folded back over the margin thereof adhered to the strip to extend into the bag.

8. A valved bag as set forth in claim 4 wherein

10

the sleeve is folded back over the margin thereof adhered to the strip to extend out of the bag.

9. A valved bag as set forth in claim 4 wherein the sleeve is folded back over the margin thereof adhered to the strip on a line spaced inwardly from the inner edge of the valve flap to have a portion extending into the bag and a portion extending out of the bag.
